United States Patent Office

Des. 182,848
Patented May 20, 1958

182,848

RAZOR BLADE

Hyman I. Pressman and Donald Pressman,
Cleveland, Ohio

Application November 4, 1957, Serial No. 48,344

Term of patent 14 years

(Cl. D22—3)

Fig. 1

Fig. 2

Fig. 1 is a top plan view of a razor blade, showing my new design; and

Fig. 2 is a top edge view thereof, the other edges presenting a similar view.

We claim:

The ornamental design for a razor blade, substantially as shown and described.
